UNITED STATES PATENT OFFICE.

FRANZ SEELAU, OF BERLIN-WILMERSDORF, GERMANY, ASSIGNOR OF ONE-HALF TO
ALEXANDER M. NEWMAN, OF BERLIN-WANNSEE, GERMANY.

ARRANGEMENT FOR PHONOGRAPHICALLY RECORDING AND REPRODUCING TELEPHONIC MESSAGES.

1,352,546.

Specification of Letters Patent. Patented Sept. 14, 1920.

Application filed November 30, 1915. Serial No. 64,210.

To all whom it may concern:

Be it known that I, FRANZ SEELAU, a subject of the German Emperor, residing at Berlin-Wilmersdorf, Germany, have invented certain new and useful Improvements in Arrangements for Phonographically Recording and Reproducing Telephonic Messages, of which the following is a specification.

10 The present invention relates to an arrangement for phonographically recording and reproducing telephone messages. Its object is to allow of the said arrangement, the cost of which is comparatively high, being better utilized by its also being used as a phonograph in the office routine. The hereinbefore named arrangement, which has frequently been termed "telephone" is employed temporarily only, owing to the 20 fact that there are not at all times telephone messages to be recorded. It is therefore obvious, that the efficiency of, or the return obtained from such arrangement, would be much greater if it were possible to put it to 25 other uses during its idle hours, for example as a dictaphone.

This is realized by means of the following invention, according to which those parts of the arrangement which phonographically record the telephone message are readily exchangeable for parts which allow of a purely phonographic employment of the apparatus, whereas those parts of the arrangement which are required in both instances, 35 remain unchanged. To this latter class of parts belong, above all, the motor with the cylinder for the record rolls, and then the mechanism for feeding the sound-box carriage. On the other hand, a part which 40 cannot be used for both duties is the sound-box, which is therefore, according to the present invention, secured in a readily detachable manner to the parts remaining for both duties. For the telephonographic service the sound-box requires a 45 suitable magnet arrangement, which, by its action on the diaphragm will cause the arriving variable or fluctuating electric current to produce phonographic oscillations. 50 The sound-box, therefore, which is constructed on what may be termed an electro-phonographic principle, cannot be used for the purely phonographic service, and, according to the present invention, a sound-box is sub-

stituted in its place, which may be termed a 55 pneuma-phonetic sound-box, or, in other words, a sound-box, in which the phonographic oscillations of the stylus or needle will, by aid of the diaphragm, produce waves in the air, which are discernible to 60 the ear as sounds. By either of these sound-boxes being brought, by means of a readily effected coupling to the carriage, in front of the phonographic record roll, the twofold use of the arrangement is rendered possible, 65 and according to the one or the other service intended, the respective sound-box is employed.

However, a simple exchange of the electro-phonetic parts for corresponding pneuma-phonetic parts will not suffice to render the apparatus completely serviceable for the respective purpose, as the electric connections required for the telephonographic record might, when the apparatus is used 70 for purely phonographic purposes, easily be the cause of trouble. This is avoided, according to the present invention, by the provision that by the exchange of the parts mentioned, the said electric connections are 75 automatically switched off.

The hereinbefore described arrangement is very advantageously simplified by providing, instead of two complete sound-boxes, a single sound-box, which is rigidly fitted 80 to the carriage, and the magnet-arrangement of which is detachable and exchangeable for a phonographic sound-tube. As is evident from the foregoing, the sound box to be employed has a diaphragm which is 85 coupled to a phonographic recording lever. According to the present invention this part of the sound-box is left non-exchangeable, and a magnet-arrangement for the telephonographic service is fitted in a suitable 90 manner, through the windings of which the telephone currents are sent, so that the diaphragm, opposite to which said magnet-arrangement is disposed, forms the intermediate, transmitting link for converting the 95 magneto-electric waves into the mechanical oscillations of the phonographic recording stylus. When the apparatus is to be used for purely phonographic service this magnet-arrangement is removed, and in its 100 place a sound-tube connection is introduced into the sound-box, so that the words spoken 105 into the horn fitted therein will act in the

well-known manner on the diaphragm as with the usual dictating machines. When the sound-box is of this construction, the telephone circuits may be switched on or off 5 in a very simple manner. The casing of the apparatus is made with a chamber to receive the magnet-arrangement, when the latter has been removed, and this receiver, as we may call it, is provided with a contact 10 arrangement. By the magnet-arrangement being placed into the receiver, the said contact arrangement is operated, so that the wires of the telephone circuits are switched off. Thus no trouble may arise from the 15 telephone circuits, after the telephonograph has been converted into a dictating machine.

In the accompanying drawing an embodiment of the present invention is shown by way of example. Figures 1 and 2 are general 20 views of the apparatus, seen from in front and from one side, respectively. Figs. 3 and 4 show, on a larger scale, a preferable form of the convertible sound box in two different positions. Fig. 5 is a diagram, indicating the connections of the telephone 25 circuits.

The apparatus comprises a box-shaped casing 1 of any approved construction in which the motor and gearing are disposed. 30 The said gearing is connected in a suitable manner with the roll cylinder 2 disposed on the top of the said box, on which cylinder 2 is placed the phonographic record roll 3. Opposite to the record roll 3 is a mechanism 35 4 for guiding and feeding the sound-box carriage 5. This mechanism consists, as may be seen in Figs. 3 and 4, of a rotary feed screw held against longitudinal movement and a stationary tube 7 inclosing the same, 40 said tube 7 having on its underside a longitudinal slot 8. On this tube 7 the carriage 5 glides by means of a tubular member 9 which, on its lower side, has an opening registering with the slot 8. Through this opening projects a nut or traveler 10 provided 45 with threads to fit those of the screw 6 and thus couple the carriage 5 and the screw 6, it being understood that the traveler or nut 10 and the carriage 5 are held to move in 50 unison lengthwise of the tube or guide 7. The nut 10 is fitted in a slot of the carriage 5 so that it may be radially displaced relatively to the screw 6 by means of the hereafter described mechanism. The said nut 55 10 has on one side a lug 11, which engages under a recess 12 in a collar 13, which is guided on the tubular member 9 of the carriage 5. The nut 10 is under the influence of a spring 14, which tends to engage said 60 nut with the screw 6. This engagement will be effected when the collar 13 is in such position that the recess 12 is directly above the lug 11. When, however, the collar is turned by means of the handle 15, the nut 65 will be forced downward and thereby the

engagement between the nut 10 and the screw 6 will be broken and the carriage disconnected from the feed mechanism. In order that the carriage be prevented from turning a second guide for the carriage is 70 provided in the usual manner by a downward projecting arm 16 on the carriage engaging with its bifurcated end around a rod 17 extending parallel to the carriage guide 7.

The sound-box is fitted to a bracket 18 on 75 the carriage 5 in such a manner that it overhangs the roll 3. In the disk-shaped part 19 of the sound-box the diaphragm 20 is fitted in the well-known manner by aid of rubber rings 21. Above the diaphragm the sound-box is formed to a sound-mouth 22, into which, by aid of a bayonet-lock 23 different insets described hereinafter may be fitted. To a bracket 24 beneath the bracket 18 is pivoted a lever 25, to the one end of which, 80 projecting beneath the box-casing 19 the recording stylus lever 26 is fitted by means of a pan and knife-edge and a spring. The stylus lever carries at its one end the recording stylus 27 and, a little farther back, 85 the reproducing stylus 28, whereas at the other end a wire 29 forms the connection with the diaphragm 20. On the collar 13 is, further, provided an upward pointing nose 30 which can engage under the lever 90 25, when the handle 15 of the collar 13 is turned downward. Thereby the stylus lever 26 is moved upward, and the styluses 27 or 28, respectively, are lifted off the record.

To the bracket 24 is, furthermore, attached a weight 31. This weight has a downward extending shoulder 32, which may bear on the nose 33 of the carriage 5, as shown in Fig. 3. In consequence thereof the lever 25 is not weighted by the weight 100 31, whereas when the parts 32 and 33 are released, the weight 31 can act on the lever 25 (Fig. 4). These two positions are obtained by the whole sound-box being pivotally fitted to the carriage, by either the 105 bracket 18 being made in the form of a fork, inclosing an arm 34 rigidly attached to the carriage guide, or, the bracket 18 being inclosed, as intermediate member, by the arm 34, this latter having the shape of a fork. 110 The whole sound box may, therefore be moved, relatively to the roll 3, in such a manner that it assumes a more or less inclined position to the latter. With the sound box in the upper position (see Fig. 3) 115 the recording stylus lever 26 receives such a position, that the sharp recording stylus 27 comes in contact with the roll 3, whereas, with the sound box in the lower position (see Fig. 4) the blunt reproducing stylus 28 120 bears against the record roll 3. At the upper position the shoulder 32 of the weight 31 bears against the nose 33, so that the lever 25 is under no-load and the sharp recording stylus 27 bears lightly against the roll 3, as 125 130

this is necessary for making the record. By the reversal into the lower position the shoulder 32 slips off the nose 33, so that the weight presses on the lever 25, in order to 5 secure the engagement of the rounded reproducing stylus 29, now coming into action, in the record groove. Both positions are secured by a lock being provided which couples the two parts 18 and 34 in either of 10 the two positions by the engagement of a pin. For this object, for example, a bolt 35 may be provided which can be extracted contrary to the action of a coiled spring disposed within, said bolt engaging, at the said 15 positions in the arm 34 fitted to the carriage. To the carriage are also fitted two pins 36, disposed beside each other (in Figs. 3 and 4 they are seen behind each other). Opposite to these pins 36 a crosspiece 37 is provided 20 on the bracket 24 and preferably made of an elastic material. When the sound-box is in recording position (Fig. 3) the crosspiece 37 bears against the pins 36. Thereby the bracket 24, which by means of screw 38 25 is pivoted to the bracket 18, is arrested. The object of this is to lock the recording stylus lever in its recording position (Fig. 3) so that lateral oscillations of the stylus 27 are obviated. In the reproducing position 30 the crosspiece 37 is lifted off the pins 36 so that the system of levers 25-26 is loose and the reproducing stylus may, therefore, freely follow the grooves made by the recording stylus, so as to reduce the wear on 35 these to a minimum.

Into the sound mouth 22 a magnet arrangement 50 may be inserted, which, as shown in Fig. 3, consists essentially of a magnet 39 and the poleshoes 41, carrying 40 each a coil 40. The whole magnet arrangement 50 is inclosed in a casing 42, which, on the side of the poleshoes is given such a shape, that it exactly fits into the sound-mouth 22 and allows of the poleshoes 41 projecting so far that these, when the arrangement is inserted, are, at a very small distance from the diaphragm 20 which is 45 preferably made of some magnetic material. This distance may be adjusted by 50 means of an adjusting attachment 43. From the winding of the coils 40 a wire 44 leads from the casing 42 and passes through the top of the box 1, as seen in Figs. 1 and 2.

The diagram Fig. 5 shows the connections 55 of the electric part of the apparatus. To the terminals 45 which may be disposed on the outside or inside of the box 1 is connected the telephone line arriving from the exchange and indicated by the arrows. The 60 current then flows within the box 1 first through the condenser 54, which is intended to bar the direct current from the exchange battery, and then through the wires 44 to the magnet coils 40. In the return path of 65 the current is provided a contact 47, which

is under action of a lever 48. This lever, which projects from the front of the casing (Figs. 1 and 2) carries a kind of tray, which serves as receiver 49 for the magnet arrangement 50, when the latter is removed 70 from the sound box. The object of this arrangement is to break the telephone circuit, when the magnet arrangement 50 is cut out.

In place of the magnet arrangement 50 a dictating speaking tube 51, or a listening 75 tube, or a horn may be inserted, each of which is provided with a tubular connection member 52, fitting exactly in the sound mouth 22.

The operation of the arrangement is as 80 follows: When a call arrives from the telephone exchange, the subscriber receives the message in the usual manner with his receiver 46. If he desires to record the conversation ensuing, he releases by means of a 85 lever indicated at 53 the motor of the telephone. For this the apparatus must be in the position for recording telephone messages, in other words, the magnet-arrangement must be fitted to the sound-box and 90 the carriage 5 must be set to the left at the commencement of the roll 3. The sound-box itself, furthermore must be in recording position. This position, shown in Fig. 3 is its upper position, at which the sharp recording stylus 27 bears against the roll and the weight 31 is lifted off the lever 25, so that the latter is under no load. By turning the handle 15 upward, the nut 10 is released, so that the carriage 5 with the sound-box 100 is coupled to the screw 6.

The telephone currents flowing through the coils 40 of the magnet-arrangement will now cause the diaphragm to oscillate, and the recording stylus 27 will follow such 105 oscillations of the said diaphragm 20. Thereby the conversation will be recorded as if by a phonograph onto the roll 3. When the conversation has ceased and the motor has been stopped, the handle 15 is first pressed 110 down, whereby the carriage 5 is released from the screw 6, and the recording lever system is lifted off the roll 3 by aid of the lug 30 on the collar 13. In consequence thereof it is possible to return the carriage 5 115 with the sound-box into its initial position. Now the magnet-arrangement 50 is removed from the sound-box and placed into the receiver 49. The contact 47, thereby operated, breaks the current circuit, so that, in case a 120 telephone call now arrives, the telephone is cut out from the telephone line. Into the sound mouth 22 of the sound-box now, a phonograph horn, or still better, a listening tube is introduced, which, as hereinbefore 125 said, are provided with suitable tubular connection pieces. Now the lever 15 is again lifted and thereby the carriage is again coupled to the screw 6, and the recording lever system 25-26 is released. The sound- 130

box is then thrown over by the bolt 35 being withdrawn and the sound-box being lowered toward the roll 3. Thereby the recording lever is so moved that the reproducing stylus 28 bears against the roll 3, engaging into the record. The weight 31 has been released by the lug 33, so that it bears on the lever 25; furthermore the locking of the bracket 24 and the lever system 25-26 have been released by the parts 36 and 37 being separated.

When, now, the motor is released, the phonographic record of the conversation recorded will be reproduced in the well-known manner. By such means the apparatus may be used for an ordinary phonographic reproduction, or as a dictating machine.

When a record is to be made as if on a dictating machine, the sound-box with the dictating tube is employed. This tube 51 is readily attached to the sound-box by the part 52 being fitted into the sound mouth 22. By adjusting the sound-box to the upper position, the recording lever system is brought into recording position, so that the recording stylus 27 bears against the roll 3 (Fig. 3). Now the recording of the dictation may proceed in the usual known manner.

It is superfluous to here describe the reproduction by the apparatus as a dictating machine, as the reproduction of telephonographically or dictaphonographically recorded conversations is identical.

In place of the phonographic recording system, also the gramophone recording system may be employed, so much the more as the whole phono-technical part of the apparatus is of a minor importance as regards the present invention, and the feature of the present invention essentially lies in the convertibility of the telegraphonic apparatus into a purely phonographic apparatus, irrespectively of the construction of the individual parts.

I claim:

1. In an arrangement for phonographically recording and reproducing telephone messages, a sound box, containing a diaphragm, a lever connected with said diaphragm, and carrying a recording and a reproducing stylus, means adapted to actuate said diaphragm by electrically produced sound waves, said means adapted to be easily introduced in the said sound box into operative relation to said diaphragm, to cause said recording stylus to record the electrically produced sound waves onto a phonographic record blank, the said means being easily removable from the sound box, and means adapted for connection with said sound box after the removal of said electrical actuating means, and adapted to receive the sound waves produced by the vi-

brations of the diaphragm when reproducing the message recorded on such blank. 65

2. In an arrangement for phonographically recording and reproducing telephone messages, a sound box containing a diaphragm, a lever connected with said diaphragm and carrying a recording and a reproducing stylus, means adapted to actuate said diaphragm by electrically produced sound waves, said means being easily removable from the said sound box, a support to 75 receive said means when so removed, a switch for automatically establishing or cutting off a connection of said electric means with a talking circuit, said switch being in such operative relation to said electric means and said support, that it will automatically establish said talking circuit, when said means are removed from said support and placed in said sound box. 80

3. In an arrangement for phonographically recording and reproducing telephone messages a sound box containing a diaphragm, a lever connected with said diaphragm and carrying a recording and a reproducing stylus, an electromagnet adapted 90 to actuate said diaphragm, said electromagnet being adapted to be easily introduced in the said sound box into operative relation to the said diaphragm to cause its vibration by the electrical sound 95 waves flowing through the coils of the electromagnet, and to cause the recording stylus to record such vibrations on a record blank said electromagnet being easily removable from the said sound box, means likewise 100 adapted for connection with said sound box, to receive the sounds produced by the diaphragm when reproducing.

4. In an arrangement for phonographically recording and reproducing telephone messages, a sound box containing a diaphragm, a lever connected with said diaphragm, and carrying a recording and a reproducing stylus, an electromagnet, adapted 105 to be easily introduced and removed from the said sound box and to actuate the diaphragm, a lever switch adapted to make or break a connection between the windings of the electro-magnet and the telephone circuit, a tray connected with the lever of said switch and adapted to receive the said electromagnet when removed from the sound box, to operate the switch by the weight of the electromagnet to break the connection 115 with the telephone circuit. 120

5. In an arrangement for phonographically recording and reproducing telephone messages, a sound box movable into a recording position and into a reproducing position and provided with a diaphragm, recording and reproducing means connected with said diaphragm and thrown into proper operative position automatically, as the sound 125

box assumes one position or the other, electrical diaphragm actuating means adapted to be removably fitted to said sound box in operative relation to said diaphragm, and 5 means likewise adapted to be fitted to said sound box removably, for receiving the sound waves produced by the diaphragm when reproducing.

6. In an arrangement for phonographically recording and reproducing telephone messages, a sound box movable into a recording position and into a reproducing position and provided with a diaphragm, recording and reproducing means connected with said 10 diaphragm, electrical diaphragm actuating means adapted to be removably fitted to said sound box in operative relation to said diaphragm, and means likewise adapted to be fitted to said sound box removably, for receiving the sound waves produced by the diaphragm when reproducing.

20 7. In an arrangement for phonographi-

cally recording and reproducing telephone messages, a sound box movable into a recording position and into a reproducing position 25 and provided with a diaphragm, recording and reproducing means connected with said diaphragm, electrical diaphragm actuating means adapted to be removably fitted to said sound box in operative relation to said dia- 30 phragm, a switch controlling the telephone circuit and arranged to be operated by the weight of said actuating means when removed from the sound box, and means likewise adapted to be fitted to said sound box 35 removably, for receiving the sound waves produced by the diaphragm when reproducing.

In testimony whereof I affix my signature in presence of two witnesses.

FRANZ SEELAU.

Witnesses:

HENRY HASPER,

LILLI FRANK.
